PUNCHBOARD

Philip S. Doumitt, Portland, Oreg.

Application August 24, 1945, Serial No. 612,398

1 Claim. (Cl. 273—139)

1

This invention relates generally to games and particularly to what is known as a punch board.

The main object of this invention is to provide a game device in which a punch board can be easily operated and by means of which the owner of the punch board will always be apprised of the fact that the board is being operated as well as the number of operations and when the punches are withdrawn therefrom.

The second object is to produce a board of the class described in which the improper operation will be discouraged and in which the holder of the board is adaptable to various sizes of punch boards.

These and other objects are accomplished in the manner set forth in the following specification as illustrated in the accompanying drawings, in which:

Fig. 1 is a perspective view of the device.

Fig. 2 is a vertical section taken along the line 2—2 in Fig. 1 showing the ejector in a retracted position.

Fig. 3 is a fragmentary view similar to the lower portion of Fig. 2 showing the ejector in an extended position.

Fig. 4 is a fragmentary horizontal section taken along the line 4—4 in Fig. 2.

Fig. 5 is a horizontal section taken along the line 5—5 in Fig. 2.

Fig. 6 is a section taken along the line 6—6 in Fig. 2.

Fig. 7 is a section taken along the line 7—7 in Fig. 2.

Fig. 8 is a longitudinal section through the punching member.

Similar numerals refer to similar parts throughout the several views.

Referring in detail to the drawing, there is shown a base 10 upon which are supported the sides 11 and the rear wall 12. Resting upon the base 10 is an ejector 13 whose slide 14 is slideable within the slot 15 formed in the base 10. A cover plate 16 extends across the ejector 13 and holds it down upon the base 10.

The ejector 13 has a rectangular opening 17 formed therein and its rearmost edge 18 is slightly behind the edge 19 of the cover plate 16 when the ejector 13 is in a retracted position, and the edge 18 registers with the forward edge 20 of the base 10 when the ejector 13 is in an ejecting position. A tab 20—A having an opening 21 formed therein projects from the forward end of the ejector 13 for the purpose of withdrawing same.

On the slide 14 is formed a block 21—A in 55

2

front of which is stretched a spring 22 on the bolts 23. Between the bolts 23 and in front of the spring 22 is placed the contact post 24 which is out of engagement with the spring 22 when the ejector 13 is completely retracted.

Upon the false bottom 10—A is mounted a dry-cell battery 25; an electric bell 26 and a buzzer 27. Cleats 10—B are secured to the base 10 and support the bottom 10—A.

One of the bolts 23 is connected to the terminal 28 of the dry cell by means of the lead 29. The terminal 28 is connected by means of the lead 30 to one side of the bell 26, the other side of which is connected to the lead 31 of the flexible cord 32 whose second lead wire 33 is connected to the binding post 34, which in turn is connected by the lead 35 to the buzzer 27, the opposite terminal of which is connected by the lead 36 to the contact post 24.

On the opposite end of the flexible cord 32 is mounted a switch body 37 within which is disposed a conical contact 38 which is connected to the wire 31. Mounted on the body 37 is a tubular handle 39 within which is mounted a plunger 40. The plunger 40 and its reduced ends 41 and 42 are metallic and the point 43 is urged away from the contact 38 by means of the spring 44 which is connected to the lead 33.

The purpose of this portion of the device is simply to provide a convenient punch end 45 by means of which the pellets 46 can be punched out of the holes 47 in the board 48.

The sides 11 have the inclined front edge 49 on which is secured a back 50. Slidable on the front side of the back 50 are the slides 51 and 52, each of which is provided with a slot 53 through which extends the bolts 54 for clamping purposes. In front of the members 51 and 52 is a cover plate 52A through which the bolts 54 extend for the purpose of clamping the slides 51 and 52 against the back 50.

Each of the members 51 and 52 is provided with a slot 55 which receives the guide strip 56 which is secured to the back 50.

Each of the slides 51 and 52 has secured thereon a side 57, both of which are provided with recesses 58 to receive the punch board 48. It is desirable to provide the pointed screws 59 which engage the edges of the punch board 48 and prevent it from being withdrawn as long as the wing nuts 60 are tightened.

It can be seen from the foregoing that the board holder readily adapts itself to a variety of widths of punch boards by merely loosening the wing nuts 60 and moving the sides 57 to the

desired position. Springs 57—A urge the sides 57 toward each other.

In the operation of the device, the player merely grasps the handle 39 in his hand and inserts the punch 45 into a hole 47 and pushes it until he has ejected the pellet 46 therefrom. This action has, however, compressed the spring 44 and contacted the members 38 and 43 thereby causing current to flow from the battery 25 to the bell 26. This action will be repeated at each punching so that the owner of the board can count, if he wishes, the number of punches. When through punching, the player merely draws on the tab 20—A, moving the ejector 13 from the position shown in Fig. 2 to the position shown in Fig. 3—that is unloading the various punchings 46 upon the table. This action, it will be noted, has caused the spring 22 to deflect and engage the contact post 24 causing current to flow to the buzzer 27 which tells the owner that the punches are being withdrawn from the device.

It will be understood, of course, that while a bell 26 and buzzer 27 have been shown, and that these are electrically operated, that lights may be substituted therefor, or mechanically operated bells, or other alarm devices can be employed without departing from the spirit of the invention.

It is desirable to provide a cover 61 over the battery 25, the buzzer 27 and the bell 26. This is preferably easily removable.

I claim:

A punchboard holder of the class described having in combination a base having a slot formed in the top side thereof constituting a guide, an ejector plate slidable on said base

having a slide attached thereto slidable in said guide, said ejector having a block on top of one end thereof, said ejector having a transverse slot formed therein constituting a pocket for which said base forms a bottom when said ejector is in a retracted position, and said slot extends beyond said base in an ejecting position, an elongated helical spring secured to said base above said slide and normal to said slot and in the path of said block, an alarm mechanism including an alarm circuit having one lead attached to said spring and another lead forming a contact in the plane of said spring and spaced therefrom when said spring is not deflected but engageable therewith when said spring is deflected by said ejector through said block whereby an electric circuit is closed when said ejector is extended and said pocket is beyond the outer edge of said base, and means for holding a punchboard over said ejector so that the punchings will enter said slot when said ejector is in a retracted position and be allowed to escape therefrom over the edge of said base when said ejector is in an ejecting position, thereby closing the circuit through said alarm mechanism.

PHILIP S. DOUMITT.
